UNITED STATES PATENT OFFICE.

FRANZ J. WOOD, OF DES MOINES, IOWA.

THRASHING MACHINE.

Application filed December 26, 1923. Serial No. 682,739.

My invention relates to that part of the thrashing machine which comprises the means for imparting motion to the grain pan and cleaning shoe.

5 The object of my invention is to provide simple, durable and inexpensive means for imparting motion to the grain pan and cleaning shoe of a thrashing machine, and to so arrange and combine the working parts there-
10 of as to minimize friction and wear, and to impart the desired movement to the grain pan and cleaner shoe with a minimum of applied power.

My invention consists in the construction, 15 arrangement and combination of the various parts of the device, whereby the objects contemplated are attained, as hereinafter more fully set forth, pointed out in my claim, and illustrated in the accompanying drawings,
20 in which:

Figure 1 shows a side elevation of a portion of a thrashing machine with my improvement applied thereto, parts of the thrashing machine being broken away to show portions of 25 the grain pan and cleaner shoe. In this figure the path of movement of the operating lever is shown by dotted lines.

Figure 2 shows an enlarged, detail, side elevation, illustrating the lever for operating the grain pan and cleaner shoe and connected parts. In this figure the operating lever is shown at its center of movement, and the dotted lines show its position at its opposite limit of movement; and

35 Figure 3 shows an edge elevation of the operating lever and connected parts, the adjacent parts of the thrashing machine being shown in section.

Referring to the accompanying drawings, 40 I have used the reference numeral 10 to indicate part of a thrashing machine frame. 11 indicates a grain pan of ordinary construction. 12 indicates a cleaner shoe of ordinary construction, and 13 indicates a power shaft. 45 The front end of the grain pan is supported on a pivoted rocker arm 14, and the rear end of the cleaner shoe is supported on a pivoted hanger 15.

Mounted upon the side of the frame 10 50 between the grain pan and the cleaner shoe is a bracket 16 supporting a bearing 17 for the operating lever. The operating lever comprises a bearing member 18 to receive the bearing member 17. Projecting downward-
55 ly from the bearing member 18 is an arm 19 for the cleaner shoe, and the cleaner shoe is

pivotedly connected to the lower end of this arm by means of the bearing member 20. Extending upwardly from the fulcrum bearing member 18 is an arm 21 which inclines upwardly and toward the delivery end of the thrashing machine and has an extension 22 at its upper end which inclines upwardly and forwardly relative to the member 21, as clearly shown in Figure 2.

60 Pivoted to the upper end of the arm 22 is a bearing member 23 connected to the grain pan 11. Midway between the fulcrum and the upper end of the operating lever there is formed an inwardly extended journal 24, upon which is mounted a wooden bearing 25, and to this bearing are attached the eccentric rods 26. The other ends of these rods are connected to the eccentric strap 27 on the eccentric 28 which is fixed on the shaft 13. 70

In practical operation, when the shaft 13 is rotated, the operating lever will be rocked and both the grain pan and the cleaner shoe will be given a reciprocating motion. When the grain pan and cleaner shoe are at one 80 limit of their movement, as shown in Figure 1, then the part of the operating lever that is connected to the cleaner shoe will be vertical, and the hanger 15 for the cleaner shoe will also be vertical. However, when the operating lever is in this position, a line from the fulcrum center to the upper end of the operating lever will be inclined upwardly and toward the receiving end of the thrashing machine, and the supporting arm 14 will also 85 be inclined upwardly and toward the receiving end of the machine at the same angle.

90 The advantage of this arrangement is that when the grain pan is operated it will be moved in a direction rearwardly and upwardly on one stroke, and downwardly and forwardly on the other stroke, thus tending to throw the straw thereon upwardly above the grain pan during its rearward stroke, and during the forward stroke the pan may move under the mass of straw and thus progressively move the straw through the machine.

95 The lower end of the operating lever has a movement from a vertical central line when at one limit of its movement, to a position inclined downwardly and toward the delivery end of the machine, when at its opposite limit of movement, and the weight of the cleaner shoe tends to return it to position with the lower part of the lever in a vertical position. 100 The grain pan, however, on account of the inclination of its supports, tends to come to 110

a position of rest at its limit of movement toward the receiving end of the machine.

By means of my improvement the weight of the operating shoe counterbalances, to a certain extent, the weight of the grain pan, and when the two are operated in unison the combined weights of the grain pan and cleaner shoe tend to assist in starting the movement of the grain pans from either end of their movement. This greatly relieves the shock and jar to the machine caused by the stopping and starting of the grain pan and cleaner shoe when at their opposite limits of movement, and requires a materially less amount of power for their operation, and this adds greatly to the durability of the machine.

Furthermore, by connecting the eccentric rods to the operating lever about midway between its fulcrum point and upper end, I am enabled to impart to the grain pan the desired length of movement, and to the cleaner shoe the desired length of movement for it.

In practice I have found that this improvement provides the necessary movement for the grain pan and cleaner shoe, with a substantially reduced amount of applied power, and that a very substantial economy has been effected in the cost of manufacture, due to the simplicity of construction and reduced number of working parts.

The opposite side of the grain pan is mounted upon a pivoted support like the support 14, but not shown, and the opposite side of the cleaner shoe has a hanging support like 15, not shown. The grain pan oscillates on its supports pivoted below it, and the cleaner shoe operates on the supports pivoted from above.

I claim as my invention:

In a thrasing machine, the combination of a machine frame, a grain pan and a cleaner shoe, said pan and said shoe being mounted to reciprocate horizontally with their inner ends slightly spaced apart and overlapping, a lever fulcrumed between its ends to the frame at a point between the grain pan and the cleaner shoe, one end of the lever being extended downwardly and pivotally connected to the cleaner shoe, the other end of the lever being extended upwardly and laterally in a direction toward the receiving end of the grain pan, means for pivotally connecting the upper end of said lever to the inner end of said grain pan, eccentric rods for imparting oscillatory movement to said lever, means for pivotally connecting one end of said eccentric rods to said lever at a point between the pivotal center of said lever and its upper end, the pivotal points of said shoe and said eccentric rods being substantially in a line passing through the pivotal center of said lever, so that when the lever is in one position of its oscillatory movement, the weight of the pivotal end of the said eccentric rods will counterbalance the weight of said shoe, at which time the pivotal center of said grain pan will be substantially vertically above the pivotal center of said lever, and when said lever is in another position of its movement, the weight of said shoe will counterbalance the weight of said grain pan, at which time the pivotal connection of said eccentric rods will be substantially vertically above the pivot center of said lever.

FRANZ J. WOOD.
